UNITED STATES PATENT OFFICE.

GASTON LUCIEN BELLIN DU COTEAU, OF BECON-LES-BRUYÈRES, FRANCE.

COIN-FREED APPARATUS.

1,318,854.

Specification of Letters Patent. Patented Oct. 14, 1919.

Application filed November 6, 1918. Serial No. 261,360.

To all whom it may concern:

Be it known that I, GASTON LUCIEN BELLIN DU COTEAU, citizen of the Republic of France, residing at 92 Rue du 22 Septembre, Becon-les-Bruyères, Seine, in the Republic of France, have invented new and useful Improvements in Coin-Freed Apparatus, of which the following is a specification.

10 This invention relates to a coin-freed apparatus specially adapted for use in hiring articles of various kinds such as books, opera-glasses, etc., said apparatus being provided with means whereby a coin to be deposited as a security for the hired article must be inserted into the apparatus previous to removing the article and is automatically refunded to the user when the article is replaced in position.

15 20 In a preferred embodiment the apparatus is composed of a casing to which the book or other article is normally locked, said casing being provided with two openings into which two coins may be respectively inserted, the value of one coin corresponding to the rent for the article and the value of the other coin corresponding to the security which is to be deposited for said article. In order to hire a book or other article it is sufficient to insert into the casing two suitable coins for instance a 25 centime piece and a 2 franc piece and to depress a button provided on the casing. The book is then freed and may be removed. When the book is thereafter returned to the apparatus, the two franc piece which had been inserted as a security is automatically refunded to the user.

25 30 35 40 45

The improved apparatus may be advantageously used in hotels, on board of ships, in railway stations, railway carriages and other public places in which apparatus provided with books or other articles to be hired have been arranged upon suitable shelves.

In the accompanying drawings given by way of example:

Figure 1 is a perspective view of a number of apparatus constructed in accordance with the invention arranged in a row on a shelf.

Fig. 2 is a perspective view of a book, in which one leaf of the cover is provided on its upper edge with a metal bar which is adapted to be hooked or locked to the apparatus.

Figs. 3 and 4 show a front elevation view and an edge view of the improved apparatus, respectively.

Fig. 5 is a vertical section along the line A—A, in Fig. 3, the deposit coin having been inserted.

Fig. 6 is a front view of the mechanism shown in the direction of arrow B in Fig. 5.

Fig. 7 is a rear view of the mechanism shown in the direction of arrow C in Fig. 5.

Fig. 8 is a horizontal section of the apparatus along the broken line D—D in Fig. 5.

By referring to the drawing, it will be seen that the apparatus comprises a casing or box 1 having a rectangular horizontal cross section and provided at the top with two sloping faces 2 between which two slots 3, 4 are formed for the insertion of two kinds of coins, the slot 3 being for instance adapted for the reception of one 25 centime piece corresponding to the renting value of the book to be hired and the slot 4 being adapted for the reception of one 2 franc piece corresponding to the amount to be left as a security.

The different apparatus offered for public use in any desired place are placed side by side on a shelf 5 (Fig. 1) upon which they are fastened by means of a ledge 6 (Fig. 3) which is provided on the apparatus and inserted behind a retaining rail 7 (Fig. 1) on the tray or shelf at the top, and at the bottom, the boxes 1 are locked by means of a hinged ledge 8 which is safely secured in place by a lock.

The books to be hired are supported by the bottom edges of their cover bearing upon ribs 9 of adjacent apparatus, said ribs being provided on the opposite faces of each apparatus. Each of the books is provided along the top edge of one half of its cover with a notched metallic bar 10 having the shape shown in Fig. 2. Said bar is inserted into a lateral slot 11 of the apparatus in which it is removably locked as hereinafter described. The upper edge of the other half of the book cover is simply guided in a slotted member 12 on the adjacent apparatus.

The operating mechanism of the apparatus comprises essentially two tilting coin chutes 13, 14 which can swing independently about a common horizontal shaft 15 and are respectively arranged below the slots 3, 4. Said chutes are adapted to receive the respective coins shown at 16 and 17 in Figs.

5, 6 and 7, which coins are temporarily retained by fingers 18, 19 pivoted on a shaft 20. The points of said fingers extend through holes 21, 22 provided in the tilting chutes 13 and 14 which are also provided with holes 23, 24 through which pins 25, 26 can extend. Said pins are carried by a horizontal bar 27 secured to a spring blade 28 which is itself fastened to the box 1 by screws 29 and carries at its upper end a push button 30.

The chutes 13, 14 are provided in their upper part with projections or teeth 31, 32 which extend at the outside of the box 1 into the slot 11 and engage respectively into notches 33, 34 in the metallic bar 10 whereby the book is locked in place. Springs 35, 36 pressing against the chutes 13, 14 act to retain the projections 31, 32 in locking position.

Arranged below the tilting chute 14 in which the two franc piece is received, is a fixed guide or chute 37 extending to a slot 38 through which the piece is delivered when the book is brought back to its normal position in the apparatus. The rear wall of the chute 37 is provided at its upper end with a horizontal part 39 acting as a temporary rest for the coin.

The operation is as follows: When a 25 centime piece and a 2 franc piece are respectively inserted into the slots 3, 4, they drop into the tilting chutes 13 and 14, respectively. They are retained in said slots by the fingers 18 and 19 and so cover the holes 23, 24 in said chutes, which are opposite the pins 25, 26. If the button 30 is then pushed inwardly, the pins 25, 26 striking the coins cause the tilting chutes 13, 14 to recede by swinging about the shaft 15 in the direction shown by arrow 40. The projections 31, 32 carried by the tilting chutes are thus withdrawn from the notches 33, 34 in the metallic bar 10 so that the book is immediately freed and pushed forward by the spring 41 (Fig. 4) secured on the box 1 in alinement with the slot 11.

As soon as the book is removed and the button 30 is released, the tilting chutes are swung in the opposite direction under the action of the springs 35, 36 and the pins 31, 32, which were formerly stopped by the edge of the notches 33, 34 bearing against shoulders formed at 42, 43 on said pins, can then project freely into the slot 11. By reason of the said additional movement of the pins 31, 32 the tilting chutes are then tilted farther forward by the springs 35, 36 to a so called intermediate position in which the fingers 18, 19 no longer project into said chutes so that the coins can drop. The 25 centime piece drops upon the bottom of the box 1 but the 2 franc piece is stopped by the edge 39 of the fixed chute 37 and remains partially in engagement within

the titling chute 14 as shown at 17' in Figs. 6 and 7. When the book is restored into place, the projections 31, 32 snap again into the notches 33, 34 of the metallic bar 10 and the tilting chutes 13, 14 are thus restored to the vertical position. The 2 franc piece slides then upon the ledge 39 and drops into the fixed guide 37 whereby it is discharged through the slot 38 into a delivery cup 44 and refunded to the user.

For the purpose of ascertaining at any time the number of the operations effected, a counter 45 is actuated every time a book is withdrawn from the apparatus, by means of a spring blade 47 secured to the upper right hand corner of the tilting chute 13. Said spring blade acts upon a ratchet wheel when the chute 13 is pushed rearwardly in the direction of the arrow 40 by pressure being applied to the button 30.

Various details may of course be changed in the construction described without departing from the invention.

Having now described my invention, what I claim as new and desire to secure by Letters Patent is:

1. A coin freed apparatus comprising in combination: a casing, a movable chute adapted to guide a coin to be preserved within the casing, a second movable chute adapted to guide a security coin to be refunded to the user upon the hired article being restored into the apparatus, a fixed coin refunding chute below said second chute and in alinement with the same when it occupies its normal position, means for retaining the coins within the movable chute when the latter occupy their normal position, means for displacing the movable chutes in one direction, said means being operative only when coins have been inserted into the movable chutes automatically operating means for displacing the movable chutes in the opposite direction to an intermediate position in which the coins escape from the said retaining means, locking members on the movable chutes co-operating locking parts adapted to be secured to the article to be hired, said locking members and parts being so constructed that the locking members and parts are disengaged from each other when the movable chutes are moved in the first mentioned direction and the movable chutes are held in their normal position so long as the locking members and parts co-operate and are brought to the said intermediate position when the article carrying the locking parts is removed from the apparatus and means for temporarily retaining the security coin within the corresponding movable chute on a level below the said retaining means when the movable chute occupies said intermediate position.

2. A coin freed apparatus comprising in

combination a casing, a tilting chute adapted to guide a coin to be preserved within the casing, a security tilting chute adapted to guide a security coin to be refunded to the user upon the hired article being restored into said apparatus, a fixed coin refunding chute below said security tilting chute and in alinement with the same when it occupies its normal position, fingers for retaining the coins within the chute when the latter occupy their normal position, a push button slidably mounted on the casing, pins connected to said push button and adapted to contact with the coins in the tilting chutes and swing the latter in one direction, resilient means for swinging the tilting chutes in the opposite direction to an intermediate position in which the coins escape from the retaining fingers, locking projections on the tilting chutes, a coöperating notched member adapted to be secured on the article to be hired, shoulders on the locking projections adapted to coöperate with the notched member and means for temporarily retaining the security coin within the corresponding tilting chute on a level below the retaining finger when the tilting chute occupies said intermediate position.

3. A coin freed apparatus comprising in combination a casing, a tilting chute adapted to guide a coin to be preserved within the casing, a security tilting chute adapted to guide a security coin to be refunded to the user upon the hired article being restored into said apparatus, a fixed coin refunding chute below said security tilting chute and in alinement with the same when it occupies its normal position, fingers for retaining the coins within the chute when the latter occupy their normal position, a push button slidably mounted on the casing, pins connected to said push button and adapted to contact with the coins in the tilting chutes and swing the latter in one direction, resilient means for swinging the tilting chutes in the opposite direction to an intermediate position in which the coins escape from the retaining fingers, locking projections on the tilting chutes, a coöperating notched member adapted to be secured on the article to be hired, shoulders on the locking projections adapted to coöperate with the notched

member, means for temporarily retaining the security coin within the corresponding tilting chute on a level below the retaining finger when the tilting chute occupies said intermediate position, a spring blade carried by one of the tilting chutes and a counter adapted to be actuated by said spring blade.

4. In coin freed apparatus, the combination with a pair of tilting chutes to receive coins, of means for moving said tilting chutes in one direction, means for moving said tilting chutes in the opposite direction beyond their original position whereby a coin may escape from one chute, and means for moving said chutes into their original position whereby a coin may escape from the other chute.

5. In coin freed apparatus, the combination with a pair of tilting chutes to receive coins, of a guide chute into which one of said tilting chutes is adapted to discharge, means for moving said tilting chutes in one direction, means for moving said tilting chutes in the opposite direction beyond their original position whereby a coin may escape from one of the tilting chutes, and means for moving the tilting chutes into their original position whereby a coin may escape from the other tilting chute into the guide chute.

6. In coin freed apparatus, the combination with a pair of tilting chutes to receive coins, of a guide chute into which one of said tilting chutes is adapted to discharge, means to prevent discharge of a coin into the guide chute from the last named tilting chute except when the latter is in a predetermined position, means for moving said tilting chutes in one direction, means for moving said tilting chutes in the opposite direction beyond their original position whereby a coin may escape from one of the tilting chutes, and means for moving the tilting chutes into their original position whereby a coin may escape from the other chute into the guide chute.

In testimony whereof I have signed my name to this specification.

GASTON LUCIEN BELLIN DU COTEAU.
